Primary Examiner — Angela J Lee(74) *Attorney, Agent, or Firm* — RG Patent Consulting, LLC; Rachel Gilboy(57) **CLAIM**

The ornamental design for an electronic device holder, as shown and described.

DESCRIPTION

FIG. 1 is an isometric view of the electronic device holder;
 FIG. 2 is a front view of the electronic device holder;
 FIG. 3 is a back view of the electronic device holder;
 FIG. 4 is a left view of the electronic device holder;
 FIG. 5 is a right view of the electronic device holder;
 FIG. 6 is a top view of the electronic device holder; and,
 FIG. 7 is a bottom view of the electronic device holder.
